UNITED STATES PATENT OFFICE.

JOHN D. DIFFENDERFER, OF EAST LEWISBURG, PENNSYLVANIA.

DESIGN FOR DESK-STANDARDS.

Specification forming part of Design No. 6,019, dated August 6, 1872.

Specification describing a certain new and useful Design for Desk-Standards, invented by JOHN D. DIFFENDERFER, residing in East Lewisburg, county of Union and State of Pennsylvania.

In the annexed drawing, Figure 1 represents an obverse view, and Fig. 2 a reverse view of my desk-standard design.

Identical parts in both figures are designated by corresponding letters of reference.

This invention has reference to a new and useful design for desk-standards; and it consists of the peculiar contour and configuration of the same, substantially as hereinafter more fully set forth.

To enable others to make and use my invention, I will proceed to describe it.

In the accompanying drawing, A refers to the front leg, and A' to the hind leg of a desk-standard embodying my design. The contour of the said legs is substantially such as that shown in Fig. 1. They are connected together, at or near their centers, by the curvilinear brace a, a short distance above the same, and at the top by means of the straight bars or braces a¹ a². These legs are further braced together, at or near their lower extremities, by the curvilinear bar a³, from which branches off a bar, a⁴, passing upward diagonally therefrom to the hind leg A', with which it unites,

and beyond which it extends a short distance so as to furnish a support for a pivot, upon which a seat at one end may be pivoted or hinged, as shown in Fig. 1. b b are small perforated plates set in the corners formed by the conjunction of the bars a¹ a² with the hind and front legs A A' of the standard. Through the perforations of these plates pass screws or like fastenings for holding the end pieces of the desk in place.

The inner or reverse side of the standard at that point prescribed by the letters a¹ a² and A A', or that part thereof which receives one end or the ends of the desk, is furnished with the shape or contour exhibited in Fig. 2, which is such as to provide the standard or standards with a rim or flange, a⁵, and plates b having parallel longitudinal projections.

Having thus described my invention, what I claim, and desire to secure by Letters Patent, is—

The design for a desk-standard, substantially as herein shown and described.

In testimony whereof I have hereunto signed my name this 15th day of June, A. D. 1872, in presence of two subscribing witnesses.

J. D. DIFFENDERFER.
